UNITED STATES PATENT OFFICE.

DAVID JAMES GREGORY, OF SCRANTON, PENNSYLVANIA.

DINING-TABLE FAN.

SPECIFICATION forming part of Letters Patent No. 398,250, dated February 19, 1889.

Application filed July 13, 1888. Serial No. 279,822. (No model.)

To all whom it may concern:

Be it known that I, DAVID JAMES GREGORY, a citizen of the United States, residing at Scranton, in the county of Lackawanna and 5 State of Pennsylvania, have invented certain new and useful Improvements in Dining-Table Fans; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to fly-fans for dining or other tables, and has for its object the provision of a fan that can be readily operated by the foot on a treadle within convenient reach, and which will be simple, compact, and 20 efficient.

The improvement consists of the details of construction, which hereinafter will be more fully described and claimed, and shown in the annexed drawings, in which—

25 Figure 1 is a perspective view of a table, showing my invention applied thereto; and Fig. 2, a sectional detail about on the line X X of Fig. 1.

The table A is of ordinary construction, and 30 is shown simply to illustrate the application of my invention. The standard B, having the fan-operating devices on its upper end, is secured to the table at its lower end, and is preferably tubular to form a case for the rod a. The block b is secured to the plate b', provided at the upper end of the standard, and has the uprights C fastened to its sides. The shaft D is journaled in the brackets d on the block b, and its ends project through openings in the uprights C and have the fans E 35 adjustably mounted thereon. The bell-crank lever F, keyed on the shaft D, has its horizontal arm connected with the rod a. The vertical arm of the bell-crank lever D is slotted, and the cross-bar f, that closes the outer end of the slot, is rounded. The shaft G is journaled in the brackets g, secured to the uprights C, and its ends are provided with fans E'. This shaft is operated from the shaft D 45 50 by any suitable interposed connections or

gearing, that shown being the arm I, which engages with the vertical arm of the bell-crank lever. This arm I is secured to the shaft G, and its lower end is bifurcated and embraces the end f of the lever F. The shaft 55 G is provided intermediate of its ends with the second fan E', which is double, being secured to the shaft by the set-screw i, which passes through the arm I.

The fans E and E' are constructed alike, 60 and are formed from sheet material, which is cut to form the wings e e and the stem e', the blank being subsequently bent to have the wings stand at an angle of about forty degrees and the stem e' to form a tube which 65 embraces the end of the shaft. The thumb-screw e² holds the fan adjustably on the shaft. The rod a passes down through the table, and is connected to the treadle J, which is supported on the stand K, connected with the 70 table by the brackets j. The inner or lower end of the treadle is provided with the plate L, which is bent to bring its ends in different planes, and is provided with pairs of brackets l and l', which are disposed on opposite 75 sides of the plate. The rod a is pivotally connected with the brackets l', and the treadle J is pivotally connected with the brackets l. The coil-spring M, mounted on the rod a and confined between the table and the plate L, 80 forces the inner end of the treadle down.

To operate the fans, the person presses down on the treadle, which effects an upward movement of the inner end of the treadle and the rod a. The pressure being removed, the spring 85 carries the treadle back to its normal position. This movement causes a vibratory motion of the bell-crank lever and a corresponding motion of the fans, which drives off the flies.

It will be noticed that the plate L is pivotally connected with the end of the treadle J, to facilitate the operation of the latter beyond what could be obtained if the said treadle were rigid from its outer end to the point of 95 connection between the said lever and the rod a, as will be readily comprehended.

Having thus described my invention, what I claim, and desire to secure by Letters Patent, is—

1. In a fly-fan, the combination, with the supports, the shafts D and G, each having fans, and the arm projecting from the shaft G, of the lever F on the shaft D, engaging 5 with the said arm, the rod *a*, and the treadle, substantially as described.

2. The combination of the table, the tubular standard having the block *b* on its upper end, the shaft D, journaled in brackets on the 10 block, the uprights C, the shaft G, journaled in brackets on the said uprights, fans on the

15 said shafts, the arm I, the bell-crank lever F, the rod *a*, the treadle J, the frame K, connected with the table, and the spring M, substantially as specified.

In testimony whereof I affix my signature in presence of two witnesses.

DAVID JAMES GREGORY.
